UNITED STATES PATENT OFFICE

WILLIAM S. MONROE, OF CHICAGO, ILLINOIS, ASSIGNOR, BY MESNE ASSIGNMENTS, TO
FULLER LEHIGH COMPANY, A CORPORATION OF DELAWARE

STEAM BOILER

Application filed May 4, 1925. Serial No. 27,704.

My present invention relates to steam boilers in which the furnace walls are adapted to be cooled by water tubes, and will be best understood from the following description and the annexed drawings, in which Fig. 1 is a side view of an illustrative embodiment of my invention, and Fig. 2 is a front elevation, with some of the parts broken away.

Like reference characters indicate like parts in the different views.

In the illustrative embodiment, the boiler has an upper steam and water drum 10 connected in the usual manner to downtake headers 11 and uptake headers 12 which, in turn, are connected by a bank of horizontally inclined water tubes 13 indicated more or less diagrammatically in Fig. 1, the boiler also having a row of water tubes 14 separated from the main bank 13 to form a chamber 15. Extending along the row of tubes 14 from the downtake headers 11 is a baffle 16, from the inner end of which extends upwardly and at an angle to the vertical, a transverse baffle 17. A baffle 18 divides the remainder 25 of the gas passages in the second and third passes. Above the water tubes 13 is a superheater 19.

Below the boiler is a furnace chamber which, in the illustrative embodiment, is provided with a chain grate stoker 20 which is located at the front of the combustion chamber with a combustion arch 21 suspended thereover, so that the gases are directed from the front toward the rear of the combustion chamber and follow a curved path as they rise to the boiler gas inlet formed between the baffle 17 and the headers 12, which inlet, it will be noted, is adjacent the rear of the furnace chamber.

40 In order to maintain the furnace walls, especially when the furnace is operated under high pressure, I provide cooling tubes 22 connected with the boiler, these cooling tubes preferably extending along the inner face of each of the side walls and separated therefrom, as shown best in Fig. 2.

In the illustrative embodiment, a lower horizontal header 23 is placed outside of each of the side walls of the furnace, and 50 correspondingly a substantially horizontal,

though slightly inclined, upper header 24 is similarly placed at the upper part of the furnace chamber and preferably adjacent the boiler gas inlet and spaced longitudinally from the header 23. The cooling tubes 22 connect the headers 23 and 24 and, in order to have the main portion of the tubes 22 inside of the side walls, I bend the ends of the tubes 22 outward so as to extend through the side walls, as shown best in Fig. 2. At the point where each tube leaves the furnace wall there is preferably provided an expansion joint and the openings for the tubes are made large enough so as to permit relative movement between the tubes and the wall, as plainly shown in Fig. 2. The joint may be of any suitable form and is shown conventionally in Fig. 2, as a plate having apertures through which the tubes pass and which covers the openings in the wall. This furnishes a seal which prevents the escape of gas while permitting the relative motion referred to above. Each header 24 is connected through a pipe 25, a junction box 26 and a plurality of small tubes 27 to the steam and water drum 10, the pipe 25 connecting with the high end of the header 24. Similarly, each header 23 is connected through a pipe 28, a junction box 29 and a plurality of pipes 30 to the drum 10.

It will be obvious that the tubes 22 are therefore connected with the water spaces of the boiler, so that as the water in these tubes is heated, it will rise through the headers 24 and the pipes connected therewith and flow as steam and water into the drum 10, the water so displaced in the tubes 22 being made up by water flowing from the drum 10 down to the header 23 and from thence up through the tubes 22.

In order to maintain the side walls effectively, I preferably arrange the tubes 22 so that they follow, in general, the path of travel of the gases in the furnace chamber. To that end, I preferably arrange the tubes as shown in Fig. 1, so that the end portions thereof are substantially straight and vertical and are connected by reverse bends. Since the header 23 is adjacent the stoker at the front of the furnace chamber and the header 24 adjacent

the gas inlet at the rear of the furnace chamber, this arrangement of the tubes 22 will cause them to extend generally in the direction of the flow of the gases from the grate 5 to the gas inlet. While obviously the tubes could extend in a straight line but at an angle to the vertical and still connect the headers 23 and 24, I preferably provide the straight portions and the reverse bends connecting them so that any inequalities in expansion 10 may be taken care of, and, at the same time, the tubes 22 may be arranged as may be desired, in order to have them follow as closely as possible the lines of flow of the gases.

15 It will also be noted that by the arrangement which I have described, the water in the cooling tubes 22 has a free opportunity to rise readily without forming steam pockets which might shut off the water circulation. 20 The inclination of the header 24 permits any steam which is carried into that header to rise readily through the pipe 25 and from thence flow to the drum 10. Thus the arrangement which I have described provides 25 a means by which the general path of the combustion gases in the furnace chamber can be paralleled, so to speak, by the cooling tubes, and, at the same time, these tubes be arranged so that a free and easy circulation 30 therethrough can be maintained.

35 In the illustrative embodiment, the stoker 20 is provided with side wall water boxes 31 connected at their front ends by pipes 32 to the downtake boiler mud drum 33 and by pipes 34 to the uptake header boxes 35. A rear water box 36 has one end connected by pipe 37 with the box 35 and the other end by pipe 38 with the end of mud drum 33. It will be seen that the side and rear water boxes 40 are connected to the water circulation so that the water may circulate freely through them and that the connections to the water boxes and to the side wall cooling tubes are independent of each other so that the circulation 45 in the one will not interfere with the circulation in the other. By locating the side wall water boxes 31 beneath the lower out-turned ends of the cooling tubes 22, as shown, the side wall is cooled throughout its height without necessitating carrying the cooling tubes too 50 close to the fuel bed on the stoker 20.

55 It will be understood that the arrangement which I have described is merely illustrative and that its embodiment may be widely varied.

I claim:

1. In combination, a furnace chamber, a steam boiler over said chamber, with the gas inlet to the boiler adjacent the upper rear 60 portion of the chamber, a grate adjacent the lower front portion of the furnace chamber, whereby the gases move from the front to the rear of the furnace chamber as they flow upward, cooling tubes adjacent the side walls 65 of the furnace and extending generally in

the direction of travel of the gases in the furnace, upper and lower headers connecting the ends of the cooling tubes and connections between said headers and the boiler.

2. In combination, a furnace chamber, a steam boiler over said chamber, with the gas inlet to the boiler adjacent the upper rear portion of the chamber, a grate adjacent the lower front portion of the furnace chamber, whereby the gases move from the front to the rear of the furnace chamber as they flow upward, substantially horizontal upper and lower headers at the sides of the furnace chamber, the lower header being adjacent the grate and the upper header adjacent the boiler gas inlet, cooling tubes adjacent the side walls of the chamber and connecting the headers and extending generally in the direction of travel of the gases in the furnace, and connections between the headers and the boiler. 75 80 85

3. In combination, a furnace chamber, a steam boiler over said chamber, with the gas inlet to the boiler adjacent the upper rear portion of the chamber, a grate adjacent the lower front portion of the furnace chamber, whereby the gases move from the front to the rear of the furnace chamber as they flow upward, substantially horizontal upper and lower headers at the sides of the furnace chamber, the lower header being adjacent the grate and the upper header adjacent the boiler gas inlet, cooling tubes adjacent the side walls of the chamber and connecting the headers and extending generally in the direction of travel of the gases in the furnace, each of said tubes 90 having straight vertical end portions and a reverse curve connecting the straight end portions, and connections between the headers and the boiler. 95 100 105

4. In combination, a furnace chamber, a steam boiler over said chamber, with the gas inlet to the boiler adjacent the upper rear portion of the chamber, a grate adjacent the lower front portion of the furnace chamber, whereby the gases move from the front to the rear of the furnace chamber as they flow upward, substantially horizontal upper and lower headers at the sides of the furnace chamber, the lower header being adjacent the grate and the upper header adjacent the boiler 110 115 120 gas inlet, cooling tubes partly within said chamber adjacent the side walls of the chamber and connecting the headers and extending generally in the direction of travel of the gases in the furnace, and connections between the headers and the boiler, said headers being exterior of the side walls and the ends of said cooling tubes being curved outwardly and extending through said walls. 125

5. In combination, a furnace chamber, a steam boiler over said chamber, with the gas inlet to the boiler adjacent the upper rear portion of the chamber, a grate adjacent the lower front portion of the furnace chamber, whereby the gases move from the front to the 130

rear of the furnace chamber as they flow upward, a horizontal lower header and an inclined upper header outside the side wall of the furnace chamber, with the lower header adjacent the grate and the upper header adjacent the boiler gas inlet, cooling tubes adjacent the furnace wall and connecting the headers and extending generally in the direction of travel of the gases in the furnace, connections between the lower header and the water spaces of the boiler and connections between the high end of the upper header and the steam and water spaces of the boiler.

6. In combination, a furnace chamber, means causing gases passing through said chamber to follow a curved path, and water tubes adjacent the side walls of said chamber, and disposed generally parallel to said path substantially throughout their lengths.

10. 7. In combination, a furnace chamber, a grate disposed adjacent the bottom thereof, a water header disposed adjacent a wall of said chamber and adjacent said grate, a gas pass to conduct the gases out of said chamber, a water header disposed adjacent said pass and adjacent said wall, and water tubes connecting said headers, said headers being spaced longitudinally from each other, and said tubes being formed with reverse curves

30 therein.

8. In combination, a furnace chamber having a chain grate stoker adjacent the bottom thereof means causing gases passing from the stoker to follow a curved path, a row of water tubes parallel to the length of the stoker and adjacent the side walls of said chamber and extending downwardly to a position a short distance above the stoker, and extending upwardly in a direction generally parallel to that of the gases rising from said stoker.

WILLIAM S. MONROE.
